UNITED STATES PATENT OFFICE.

JOHN L. LANDENBERGER, OF PHILADELPHIA, PENNSYLVANIA.

ADDING MACHINE.

Application filed March 14, 1921, Serial No. 452,379. Renewed July 12, 1922. Serial No. 574,544.

To all whom it may concern:

Be it known that I, JOHN L. LANDENBERGER, a citizen of the United States, residing in Philadelphia, Pennsylvania, have 5 invented an Adding Machine, of which the following is a specification.

My invention relates to adding machines, the object of the invention being to provide a novel, improved and simplified device 10 whereby computations may be made mechanically and accurately and with great rapidity.

The invention will be more readily understood from the attached drawings, in which:

15 Fig. 1 is a face view of the device detached from the casing;

Fig. 2 is a diagrammatic section on the line 2—2, Fig. 1;

20 Fig. 3 is a plan view showing two of the superimposed numeral discs in proper relative positions, and illustrating the details of the construction;

25 Figs. 4 and 5, are respectively face views of the preferred form of numeral disc, reduced in size, and of a modified form of partition;

30 Fig. 6 is a view illustrating a form of fastener to replace the eyelet shown in Fig. 2 when the partition of Fig. 5 is employed;

35 Fig. 7 is a view in perspective of the casing with the device in place, and

Fig. 8 is a fragmentary enlargement of a portion of the device illustrating details of construction.

35 With reference to the drawings, my device comprises, in the form illustrated, a face plate 1 and a back plate 1^a, which may be made of thin metal, cardboard, celluloid or other suitable material, said plates being

40 in the present instance rectangular in form and having inserted therebetween a series of superimposed discs 3, 4, 5, 6 and 7, with a series of suitable baffle plates 8, 8, interposed between and separating the respective discs, one from another. The face and back plates and the respective discs and baffles are secured together in the present instance

45 by a suitable fastener 2 at the center, said fastener being in the form of a short cylinder or eyelet which extends through central apertures in the respective elements and has its ends upset or riveted over at the surfaces of the face and back plates. The

50 said eyelet not only secures the elements to-
gether, but functions as an axle or spindle 55 about which the said discs are rotated.

As clearly indicated in the drawings, the discs are of different diameters, the bottom disc being the largest and the remaining discs decreasing in diameter progressively 60

toward the top. The baffle plates 8, 8, are in the present instance in the form of elongated strips which extend diagonally from one corner of the cover plates to the opposite corner, as clearly shown by the dotted line, Fig. 1, with the exception of the top baffle which extends only from one corner to the inner edge of the slot 12. The object of these baffle plates is to separate the discs and to provide means for frictionally retaining said discs in a given position under normal conditions, there being sufficient friction between the discs and the baffle plates to accomplish this result.

The elements, after being secured together 75 in the manner described, are preferably mounted in a suitable casing, said casing in

the present instance consisting of an envelope 20, in which the face and back plates and associated elements neatly fit, said envelope being open at one edge 21 to admit

the device, and having an opening 22 in one side thereof to expose the working portions of the face, hereinafter described, to permit

operation of the device. The case may vary 85 widely in form, but should be adapted to hold the various parts of the device in their proper relative positions.

As clearly illustrated in Fig. 3, each of the said discs 3, 4, 5, 6 and 7, is perforated 90 with a series of apertures 9 which in each case are disposed in a circle concentric with the axis of rotation of the discs and at a point slightly within the periphery of the discs, the apertures in each of the discs being so located that the edge of the next

smaller and superimposed disc lies substantially at the inner edges of the said apertures, as indicated in Fig. 3. The discs 4, 5, 6 and 7, are each provided with a series 95 of notches 10 at the periphery, said notches being spaced apart and extending completely around the periphery of the discs.

The disc 3 is, in the present instance, divided into four quarters, and each quarter 100 section contains sixteen of the apertures 9, evenly spaced, and representing each an increment of one-sixteenth of an inch. The

disc 4 also is divided into four quarters, and each quarter contains twelve of the apertures 9, each representing an increment of one inch. The discs 5 and 6 are divided also 5 into four quarters, each quarter containing ten of the apertures 9 and each aperture of the disc 5 representing one foot, while each of the apertures of the disc 6 represents an increment of ten feet. The disc 7 is divided 10 into halves, each of which contains ten of the apertures 9 representing each an increment of one hundred feet. The apertures of the respective divisions are designated by figures marked or otherwise suitably placed 15 upon the discs opposite the respective apertures, the figures starting at zero at one end of each of the said divisions, and being numbered in the present instance in a counter-clockwise direction, as is clearly shown in 20 Fig. 3.

In the upper face 1 is a series of segmental slots 11, said slots being disposed to respectively overlie the series of holes 9 in the respective discs 3, 4, 5 and 6, while a semi-circular slot 12, also formed in the said upper face, overlies the series of apertures 9 in the disc 7. Each of the said slots 11 has an extension 13 at their lower ends, which extensions are offset inwardly from the said 25 slots 11, as shown in Figs. 1 and 9, and are arranged respectively to overlie the said recesses 10 in the peripheries of the discs 4, 5, 6 and 7. The said face 1 has also a slot 14 radially disposed from the center 2, and of 30 sufficient length to extend over a portion of each of the said discs and to expose figures upon the discs which lie opposite and designate the respective apertures 9. It will be noted that the slots 11 each extend over an 35 arc of 90° , and that the slots are marked at their edges to correspond with the number and spacing of the apertures 9 in one-quarter division of the discs which they respectively overlie, the said markings being designated 40 by the same figures appearing opposite the corresponding sets of apertures on the respective discs. The slot 12 is semi-circular and is marked to accord with the apertures and 45 designations of the respective halves of the disc 7. It is further to be noted that the line of the lower end of the slots 11 and 12 is disposed radially to the center 2 and that the slot 14, also radial to the said center, is disposed at an angle of 90° to the said line 50 of the lower ends of the slots 11 and 12. It will be apparent that with this arrangement the figures appearing under the slot 14 will be the same as those designating the apertures appearing at the lower ends of the slots 55 11 and 12, with the exception of the top disk 7.

Means is provided for distinguishing the quarter or main divisions of the discs as they appear under the slots 11, and for this purpose the respective sections may be given dis-

tinctive colors, or, as illustrated in the drawings, the sections may alternate in color, it being only necessary to indicate as the discs are rotated when one section passes from under the lower end of the slots 11 and the next following section appears. It is also desirable to indicate under the slot extensions 13 the completion as described above of the respective main sections of the discs 4, 5 and 6, and this is accomplished by means of suitable indicating marks 25 at the peripheries of the respective discs opposite the respective zero apertures, as shown in Fig. 3, said marks appearing under the slot extensions 13 as the discs are rotated.

In operating the device, the procedure is as follows: At the start of each new problem the machine must be set at zero. This may be accomplished by inserting the point of a pencil or suitable stylus in the apertures 9 of the respective disks which appear under the slots 11 and 12, and rotating the disks until a zero-designated aperture lies in each case at the bottom of the respective slots, only zeros appearing under the total slot 14. For the sake of example, we will suppose now that it is desired to make the following addition: Five feet, six and one-half inches, and one foot, six and three-fourth inches. It is first necessary to register under the total slot the first of these dimensions. In accomplishing this, the procedure is as follows: A pencil or similar sharp pointed instrument is inserted through the outermost slot 11 and into the aperture 9 in the disk 3 which lies opposite the designation " $\frac{1}{2}$ " on the face of the casing, the pencil being moved in the slot in a clockwise direction and advancing the said aperture 9 which it has engaged to the bottom of the slot. The pencil is then inserted through the next adjacent slot 11 and into the aperture 9 of the disk 4 which lies opposite the marking " 6 " on the face of the casing, the pencil again being moved in a clockwise direction to advance this aperture also to the bottom of the slot 11. The same procedure is followed with the disk 5, the pencil being inserted in the aperture 9 lying opposite the figure " 5 " on the casing, and being advanced to the bottom of the slot. At the end of this operation, there should appear marked up under the total slot 14, five feet, six and one-half inches. In adding to this the one foot, six and three-fourth inches length, the following procedure is followed: The pencil is inserted through the outermost slot into the aperture 9 in the disk 3 which lies opposite the designation " $\frac{3}{4}$ " on the face 1, and the said aperture being carried in the manner previously described to the bottom of the slot. It will be noticed in this procedure that the aperture 9 into which the pencil has been inserted lies in a main division of the disk 3 different from the division in

which the aperture occupies the bottom of the slot, and that accordingly as the said first-named aperture is carried down to the bottom of the slot, the color appearing under the slot at the base thereof changes, thereby indicating the necessity for sliding the pencil point over into the notch 10 in the periphery of the disk 4 which lies opposite the bottom of the slot 11, and thereafter 10 drawing the pencil down into the extension 13 to advance the said notch to the bottom of said extension. The necessity for this will be understood when it is noted that each main division of the disk 3 corresponds to 15 one sub-division of the disk 4, and that accordingly having rotated the disk 3 so as to complete one full division thereof, it is necessary to advance the disk 4 through one sub-division to cause the marking up of 20 this addition in the total column.

The next step is to insert the pencil in the next adjacent slot 11 and into the aperture 9 lying opposite the mark "6" of this slot, this aperture then being advanced to the bottom 25 of the slot 11 in the usual manner. Here again it is noted by the changing of the colors under the base of the slot 11 that one main division of the disk 4 has been completed, when it is accordingly necessary in this case also to slide 30 the point of the pencil over into the notch in the disk 5 which lies opposite the bottom of the said slot 11 and to carry this notch to the bottom of the extension 13. The pencil is then inserted through the next slot 35 11 and into the aperture in the disk 5 which lies opposite the indication "1" on the face plate adjacent the said slot, said aperture being advanced to the bottom of the slot in the manner described. In this instance, 40 the color appearing under the bottom of the slot 11 does not change, so that it is unnecessary to register an added advance on the next disc 6. There should now appear under the slot 14, a total of seven feet, one and one- 45 fourth inches.

If in advancing any one of the disks 4, 5 or 6, by means of the notches 10 at the peripheries thereof, there appears under the slot extension 13 one of the marks 25, it 50 will be necessary to advance the next higher disk through one sub-division, this being necessary since the appearance of the said mark 25 under the extension 13 indicates that one main division of that disk has been 55 passed through and should be noted on the next higher disk, one sub-division of which corresponds to the main division of the lower disk.

As shown in Fig. 4, it is preferred to reinforce 60 the central apertures 15 of the disks through which the eyelet passes by means of a suitable reinforcing member of metal or other suitable hard material, this being particularly desirable where the modification 65 illustrated in Figs. 5 and 6 is employed.

Fig. 6 illustrates a fastener 2* of the cotter pin type, which may replace the eyelet 2 illustrated in Fig. 2, this fastener 2* passing through slots formed in the upper and back faces 1 and 1* and being separated at 70 the back in the usual manner to hold it in place. In this case, I prefer to employ partitions of the form illustrated in Fig. 5, these partitions being circular in form and having therein a slit 16 through which the said 75 fastener passes. The diameter of this partition, of course, will be limited so as not to interfere with the slots 11 and 12. It will be clear that in this form of the device 80 the disks as formerly will be permitted to turn freely on the fastener as a pivot, whereas the partitioning elements will be held stationary.

It will be clear that although I describe the device as an adding machine, the use of 85 the device need not be limited to the operation of addition, and that furthermore it may be employed by proper modification within the scope of the invention for adding other than feet, inches and fractions, the 90 device being capable of modification to enable its use with any system of figures; nor is it necessary to limit the number of disks to the number shown and herein described, 95 since any number of disks may be employed, and the number of main divisions of the respective disks is entirely one of choice. The device may also be used without a casing, although some form of casing has been found desirable, it being only necessary to 100 secure in any suitable manner the face and back plates with the baffle plates to hold them relatively immovable, while permitting free rotation of the disks. It is also to be understood that though in the claims "apertures" and "recesses" are specified, these 105 terms are to be considered as covering any means whereby the point of a pencil or stylus may take hold of the discs to permit the latter being rotated.

Considerable modification both in form and in the disposition of the elements is possible with no departure from the essential features of the invention.

I claim:

1. In a machine of the type specified, a plurality of superimposed discs diminishing in diameter toward the top, each of said discs having a series of apertures in that portion extending beyond the edge of the overlying disc, and each of said discs overlying the bottom disc having a series of recesses at the edge corresponding with its said apertures.

2. In a machine of the type specified, a plurality of superimposed discs diminishing in diameter toward the top, each of said discs having a series of apertures in that portion extending beyond the edge of the overlying disc, and each of said discs over-

lying the bottom disc having a series of recesses at the edge corresponding with its said apertures, and a cover plate having slots disposed over the apertures and recesses 5 of the respective discs.

3. In a machine of the type specified, a plurality of superimposed discs diminishing in diameter toward the top, each of said discs having a series of apertures in that 10 portion extending beyond the edge of the overlying disc, and each of said discs overlying the bottom disc having a series of recesses at the edge corresponding with its said apertures, and a cover plate having 15 slots disposed over the apertures, with offset extensions overlying the recesses of the respective discs.

4. In a machine of the type specified, a plurality of superimposed discs diminishing 20 in diameter toward the top, each of said discs having a series of apertures in that portion extending beyond the edge of the overlying disc, and each of said discs overlying the bottom disc having a series of recesses 25 at the edge corresponding with its said apertures, and a cover plate having slots disposed over the apertures of the respective discs, with offset extensions over the recessed edge of the immediate overlying disc.

5. In a machine of the type specified, a plurality of superimposed discs diminishing in diameter toward the top, each of said discs having a series of apertures in the exposed portion disposed in a circle concentric with the disc, and each of the discs being divided into a plurality of equal main sections, and a cover plate having therein a series of arcuate slots drawn on the circumferences 35 of circles and respectively overlying the series of apertures in the respective discs, said slot in each case being equal in length to one main division of the disc which it overlies.

45 6. In a machine of the type specified, a plurality of superimposed discs diminishing in diameter toward the top, each of said disks having a series of apertures in the exposed portion disposed in a circle concentric with the disc and being divided into a plurality of equal main sections, the said main sections being divided by said apertures into a plurality of sub-sections, the main section 50 of each disk corresponding to one of the sub-divisions of the immediate overlying disk, and the sub-divisions of each main division representing a fractional part of the sub-division of the next overlying disk, a cover plate having therein a series of arcuate slots drawn on the circumferences 55 of

circles and respectively overlying the series of apertures in the respective disks, said slots in each case being equal in length to one main division of the disk which it overlies and having its length divided by suitable 65 markings on the said cover plate into a number of divisions corresponding with the subdivisions of the respective disks.

7. In a machine of the type specified, a plurality of superimposed disks diminishing in diameter toward the top, each of said disks having a series of evenly spaced apertures in the exposed portion disposed in a circle concentric with the disk, and each of the disks being divided into a plurality of 70 equal main sections correspondingly subdivided by said apertures, the said disks overlying the bottom disk having extending around the edges thereof series of evenly spaced recesses corresponding in number to the apertures in the respective disks, and a cover plate having therein a series of arcuate slots drawn on the circumference of circles and respectively overlying the series of apertures in the respective disks, said slot in each case being equal in length to one main division of the disk which it overlies 75 and having at its lower end an offset extension overlying the recessed edge of the immediate overlying disk.

8. In a machine of the type specified, a plurality of superimposed disks diminishing in diameter toward the top, each of said disks having a series of evenly spaced apertures in the exposed portion disposed in a circle concentric with the disk, and each of the disks being divided into a plurality of equal main sections correspondingly subdivided by said apertures, the said disks overlying the bottom disk having extending around the edges thereof series of evenly spaced recesses corresponding in number to the apertures in the respective disks, a cover plate having therein a series of arcuate slots drawn on the circumference of circles and respectively overlying the series of apertures in the respective disks, said slot in each case being equal in length to one main division of the disk which it overlies and having at its lower end an offset extension overlying the recessed edge of the immediate overlying disk, means indicating the points of division between the said main divisions of the respective disks and adapted to appear under the said main slots, and means for indicating the said main divisions of the disks overlying the bottom and underlying the top disk and adapted to appear under the said slot extensions.

JOHN L. LANDENBERGER.
